DESIGN FOR A DRAFT CONTROLLING DEVICE

Morris W. Crew, Cleveland, and Clarence H. Morrow, Shaker Heights, Ohio, assignors to The Hotstream Heater Company, Cleveland, Ohio, a corporation of Ohio

Application December 20, 1941, Serial No. 104,772

Term of patent 14 years

To all whom it may concern:

Be it known that we, Morris W. Crew and Clarence H. Morrow, citizens of the United States and residents of Cleveland and Shaker Heights, respectively, in the county of Cuyahoga and State of Ohio, have invented a new, original, and ornamental Design for a Draft Controlling Device, of which the following is a specification, reference being had to the accompanying drawing forming a part thereof.

In said drawing, Fig. 1 is a front elevational view of a draft controlling device, showing our

new design; Fig. 2 is a side elevational view thereof; Fig. 3 is a rear elevational view thereof; and Fig. 4 is a vertical sectional view thereof, as taken on the line 4—4 of Fig. 1. In all views, the damper or flutter of the device is shown in its closed position.

We claim:

The ornamental design for a draft controlling device, as shown and described.
